UNITED STATES PATENT OFFICE.

WILLIAM H. MUZZY, OF CHICAGO, ILLINOIS.

FUEL-FEEDING DEVICE FOR AUTOMOBILES.

1,392,652.

Specification of Letters Patent.

Patented Oct. 4, 1921.

Application filed April 10, 1920. Serial No. 372,836.

To all whom it may concern:

Be it known that I, WILLIAM H. MUZZY, a citizen of the United States, residing at Chicago, in the county of Cook and State 5 of Illinois, have invented certain new and useful Improvements in Fuel-Feeding Devices for Automobiles, of which I declare the following to be a full, clear, and exact description.

10 This invention relates to improvements in fuel feeding systems for automobiles and has more particular relation to improvements in the so called "vacuum tanks" employed for feeding the fuel from a tank at 15 the rear of the machine to a convenient point adjacent to the carbureter and from this point feeding it as required to the carbureter.

One of the principal objects of the invention is to provide a tank which is electrically operated by the electric devices 20 forming part of the regular running equipment of the automobile.

A further object of the invention is to 25 provide a vacuum tank of simple and cheap construction and having a large capacity for delivering gasoline.

A still further object of the invention is 30 to provide a simple and cheap electrically operated tank.

The invention also has other objects all of which will be hereinafter more particularly set forth and claimed.

In the accompanying drawings forming 35 part of this specification:

The figure represents a central vertical section of my improved form of tank, the wiring and controlling parts of the regular automobile equipment being shown in dia- 40 gram.

In the aforesaid drawings 1 represents the outer shell of the vacuum tank, 2 the inner receptacle, 3 the cover for the latter, 4 the attaching nipple for the suction pipe connected to the manifold of the engine as usual, 5 the nipple for the connection of the pipe which leads to the main fuel supply tank usually located at the rear of the machine. Gasoline discharges from the chamber 2 into the shell or chamber 1 through a flapper valve 6 loosely mounted by headed studs over the lower open end of a passage formed in an elbow 37, which passage connects with the chamber 2. This construction and operation is old and well known in

the art and is shown in the patent to Webb Jay No. 1,125,549 dated Jan. 19th, 1915.

A discharge nipple 7 connects with the carbureter of the engine. The upper edge of the shell 1 is provided with a cast ring 40 forming a support for a flange 41 on the upper edge of the inner receptacle 2.

The top 3 is secured in position over the flange 41 by screws 13, a cork washer 39 being interposed at this point to provide an air tight joint.

A rod 10 is guided at its lower end by an apertured plate 11 secured to the bottom of the receptacle 2 but allowing gasoline to pass freely into the elbow 37. This rod 10 carries a cork float 8 at its lower end and an air valve 17 near its upper end and is further provided with an operating nut 16 fast thereto. The upper end of this rod 10 is guided through an aperture formed in the upper wall of a cage 19 which is mounted on a plate 15. This plate is fast on the upper end of a brass sleeve 14, the lower end of this sleeve being threaded and screwed into the top 3. A companion plate 15 is also mounted near the lower end of the sleeve 14. These two plates 15 form the supports for the winding or bobbin wires 25, which are properly insulated and which with the sleeve 14 form an operating solenoid.

The float 9 carries a soft iron sleeve 12 which may be either made solid as shown or may be constructed of a series of soft iron wires soldered together in a manner well known in the art. This sleeve 12 is loosely mounted on the rod 10 so that it may slide freely up and down thereon.

The upper end of the rod 10 is arranged, when it is forced upward to contact with a spring contact arm 23 and bring this arm into contact with a companion arm 22 to close a shunt circuit at this point. The arms 22 and 23 are secured to insulating blocks 21 and 24 which are secured together and to a casing 20, mounted on top of the cage 19 and fully inclosing the contacts.

The cage 19 is formed with a series of air ports 18 which are left free as shown or may be covered by fine screen netting if desired.

The timing shaft 36 of the engine carries the usual cam block 37 which contacts with a roller on the pivoted contact arm 35 and thus separates the contact of this arm from the contact of the contact screw 34 which is

85

105

110

suitably mounted on the insulated base 45. This screw 34 is connected to a battery 31 by a wire 33. A wire 46 connects the opposite pole of the battery to the primary winding 5 of the usual spark or induction coil 32. A wire 29 connects this primary winding of the coil to the bobbin wire 25. A wire 30 connects the contact arm 35 to the opposite end of the wire 25.

10 It will be seen from the above that the current passes through the bobbin 25 of the solenoid every time the primary circuit of the engine ignition devices is closed, except at such times as when the upper end of the 15 rod 10 is holding the contacts 22 and 23 together and at this time the circuit is shunted through the wires 27 and 28.

The operation of the device is as follows:

When the floats are both down as shown 20 in the drawings, the atmosphere valve 17 is closed and held so against the buoyancy of the fully submerged float 8 because of the vacuum in the chamber 2 formed by the suction from the engine manifold to which 25 the chamber 2 is connected. In this position of the devices the gasoline from the main tank is flowing into the receptacle 2 through the attaching nipple 5. The current is passing through the bobbin wires 25 30 a great number of times per minute according to the speed of the engine. As the gasoline in the chamber 2 rises above the level shown in the drawings, the float 9 moves upward, and the upper end of the soft 35 iron sleeve 12 is moved up into the brass tube 14 and into the field of attraction of the solenoid. Both the float 9 and the sleeve 12 are then forced upward step by step, by the action of the solenoid and by the rising 40 float until the upper end of the sleeve contacts with the nut 16 when the valve 17 is forced off of its seat, against the force of the atmospheric pressure which is holding it down, by the impulse of the solenoid 45 added to the buoyancy force of the float 8.

The impulses of the solenoid at high engine speeds are so close together that there is practically a steady pull on the sleeve 12 and it would remain suspended at such 50 times in its upper position if no means were provided for breaking the flow of impulses. This means I provide however in the contacts 22 and 23. When the rod 10 is moved upward as above described the upper end of 55 the rod forces the contact 23 against the contact 22 and the circuit is shunted from the bobbin of the solenoid to the wires 27 and 28. The sleeve 12 is thus released and the sleeve and the float 9 drop as the gasoline 60 descends in the chamber 2. As the rod 10 however is independently supported by the float 8 and as this float is fully submerged at this time, the contacts 22 and 23 remain closed and the float 9 and sleeve 12 gradually descend as the gasoline passes down

through the valve 6. It will of course be understood that when the valve 17 is raised atmospheric pressure enters the chamber 2 and the gasoline descends from this chamber through the valve 6 and flows into the shell 1. By the time the gasoline level descends enough to effect the float 8 the sleeve 12 has passed well out of the active influence of the solenoid, and when the contacts 22 and 23 finally separate and allow the current to again flow through the solenoid, the sleeve 12 will not be operated. As the gasoline descends in chamber 2 the float 9 is lowered until it contacts with the upper side of the float 8. As the gasoline 80 continues to descend the combined buoyancy level of the two floats is reached and the float 8 descends from its upper position to its lower position and the valve 17 is thereby closed and the pumping operation is repeated until the float 9 again rises and the sleeve 12 through its operation by the solenoid again opens the air valve.

It will of course be understood that the sleeve 12 is longer than the solenoid bobbin 90 and for this reason will seek to center itself in the bobbin with an increasing force as it passes upward step by step and will finally deliver sufficient of a blow or impulse against the nut when it reaches it to force the valve 17 95 off of its seat. This hammer blow is particularly desirable in devices for opening a valve drawn or held closed by atmospheric pressure as the hammer blow will open the valve when a certain amount of force is available 100 where a steady pressure with the same force might not open it. It is of course understood that the solenoid is particularly adapted to such a use as its action in an intermittent circuit is especially of a tapping blow 105 type but a solenoid of sufficient strength might of course be employed to force the valve open by a steady push.

I do not care to limit myself to an electrically operated tank dependent upon the regular ignition devices of the machine as it will be apparent that suitable circuit closing devices might be easily attached to some moving part of the engine and connected to the tank independently of the 110 regular circuits.

It will of course be appreciated that with such circuit closing devices and at slow engine speeds with the devices as shown the shunt circuit controlled by the contacts 22 120 and 23 might be omitted as the impulses sent through the solenoid could be so spaced that the sleeve 12 could drop out of the active influence of the solenoid between its impulses, when the gasoline has descended so that the 125 float 9 no longer supports the sleeve.

The windings of the solenoid add very little resistance to the passage of the current while the solenoid is in action and consume less than one ampere when active. It 130

will of course be understood that the active period of the solenoid is very brief as the pumping action of the tank is rapid when it is drawing gasoline but as its capacity is 5 greatly in excess of the gasoline consumed by the engine, its inactive period is quite extended and during this latter period no current is passing through the solenoid.

It will of course be understood that the 10 gasoline descends by gravity from the outer atmospheric chamber 1 to the carburetor in a manner well known in the art and shown in the aforesaid Jay patent. It will also be understood that by including the actuating 15 circuit for the tank in the interrupted circuit of the regular ignition of the machine the need of providing any make or break devices at or near the tank, is obviated. As before stated the shunt circuit, at slow 20 speeds of the engine, may be eliminated and the device operated entirely from the make and break of the ignition devices, the sleeve 12 and its float making step by step movements downward between successive impulses 25 of the solenoid when the float is no longer supported by the gasoline. In this application of the invention the intermittent action of the circuit is necessary to allow the sleeve 12 to move downward, as it drops 30 slightly between each impulse.

I claim—

1. In a vacuum tank, the combination with a vacuum chamber, of a suction connection therefor, a connection feeding gasoline thereto, an atmosphere valve for said chamber, mechanical means within the chamber controlled by the liquid level thereof for operating the valve and additional means, electrically operated, for supplementing said mechanical means for opening the valve.

2. In a vacuum tank, the combination with a vacuum chamber, of a suction connection therefor, a connection feeding gasoline thereto, an atmosphere valve for the chamber, a float in the chamber, means controlled by the float for electrically operating the valve and an independent float for the valve.

3. In a vacuum tank, the combination with a vacuum chamber, of a suction connection therefor, a connection feeding gasoline thereto, an atmosphere valve for the chamber, a float for supporting the valve, and electrically actuated devices for operating the valve.

4. In an automobile the combination with ignition devices including a primary circuit and make and break devices therefor, of a fuel feeding device, and electrical means included in said circuit for actuating the said fuel feeding devices with a step by step movement.

5. In an automobile the combination with 65 ignition devices including a primary circuit

and make and break devices therefor, of a fuel feeding tank, an atmosphere valve for said tank, and means included in said circuit for actuating said valve with a step by step movement.

6. In an automobile the combination with 70 ignition devices including a circuit and make and break devices therefor, of a fuel feeding device, an electrical actuator for the fuel feeding devices included in the circuit 75 and a float controlling the actuator.

7. In an automobile the combination with 80 interrupted circuit devices operated by the engine, of a fuel feeding device, and electrical controlling means for the said feeding device included in the circuit and having a step by step operation.

8. In an automobile the combination with 85 interrupted circuit devices operated by the engine, of a fuel feeding device, an atmosphere valve for said feeding device, and electrical means for operating the said valve included in the circuit and having a step by step operation.

9. In an automobile the combination with 90 circuit devices forming a part of the regular running equipment of the engine, of a fuel feeding device included in and controlled by the circuit and having a step by step operation.

10. In an automobile the combination with 95 an ignition circuit, of a fuel feeding device included in and controlled by the circuit and having a step by step operation.

11. In a vacuum fuel feeding tank, the 100 combination with a vacuum chamber having a suction connection and a gasoline inlet and outlet, of an electrically controlled atmosphere valve for the vacuum chamber and a float for holding said valve open.

12. In a vacuum fuel feeding tank, the 105 combination with a vacuum chamber having a suction connection and a gasoline inlet and outlet, of an atmosphere valve for the vacuum chamber, a float and electrical means 110 for opening the valve, and independent devices for breaking the circuit for said means when the tank is full.

13. In an automobile the combination with 115 ignition devices, of a fuel feeding device having an electrical control included in the ignition circuit, and means controlled by the fuel feeding devices for shunting the circuit from the electrical control.

14. In an automobile, the combination 120 with ignition devices, of a vacuum fuel feeding tank, an electrical control for the tank included in the ignition circuit and having a step by step operation, and a float and connections in the tank governing the electrical 125 control.

15. In an automobile the combination with 130 ignition devices of a vacuum fuel feeding tank, a solenoid on the tank included in the ignition circuit, an atmosphere valve, and a

- float carrying an armature co-acting with the solenoid to operate the valve.
16. In an automobile the combination with ignition devices of a vacuum fuel feeding tank, an electric operator for the tank included in the ignition circuit, an atmosphere valve, a float and armature for operating the valve, and an independent float connected to the valve.
- 10 17. In an automobile the combination with an electric circuit controlled by the engine, of a vacuum fuel feeding tank, an atmosphere valve for the tank, an electromagnet included in the electric circuit and located 15 outside of the tank, and a float and armature in the tank and co-acting with the electromagnet to operate the atmosphere valve.
18. In an automobile the combination with 20 an ignition circuit including a make and break device, of a vacuum tank for feeding the fuel, an atmosphere valve for the tank,
- an electric actuator on the outside of the tank included in the ignition circuit, a float and armature within the tank co-acting with 25 the actuator to open the atmosphere valve, independent means for holding the valve open, and devices for rendering the electric actuator inactive.
19. In a vacuum tank the combination with 30 a vacuum chamber, of a suction connection therefor, a connection feeding gasoline thereto, an atmosphere valve for said chamber, means for operating the valve within the tank, and magnetic devices exterior of 35 the tank for actuating the operating means within the vacuum chamber through the intact walls of the same.

In testimony whereof I affix my signature in the presence of two witnesses.
